[57] CLAIM

The ornamental design for a fluid dispensing module for dispensing heated fluids, such as hot melt adhesives, sealants or caulk, as shown and described.

DESCRIPTION

FIG. 1 is a front elevational view of a new design for a fluid dispensing module for dispensing heated fluids, such as hot melt adhesives, sealants or caulk;

FIG. 2 is a left side elevational view of the fluid dispensing module for dispensing heated fluids, such as hot melt adhesives, sealants or caulk of FIG. 1;

FIG. 3 is a bottom plan view oriented according to FIG. 2; FIG. 4 is a rear, elevational view of the fluid dispensing module for dispensing heated fluids, such as hot melt adhesives, sealants or caulk of FIG. 1;

FIG. 5 is a top plan view, oriented according to FIG. 6;

FIG. 6 is the right side elevational view of the fluid dispensing module for dispensing heated fluids, such as hot melt adhesives, sealants or caulk of FIG. 1;

FIG. 7 is a rear perspective view of the fluid dispensing module for dispensing heated fluids, such as hot melt adhesives, sealants or caulk; and,

FIG. 8 is a frontal perspective view of the fluid dispensing module for dispensing heated fluids, such as hot melt adhesives, sealants or caulk.
